Primary Examiner—Louis S. Zarfas*Assistant Examiner*—Inga-Maria Hyttinen*Attorney, Agent, or Firm*—Flynn, Thiel, Boutell & Tanis, P.C.[57] **CLAIM**

The ornamental design for a fishing lure with decorative side panels, as shown and described.

DESCRIPTION

FIG. 1 is a front view of a fishing lure with decorative side panels embodying my new design;

FIG. 2 is a rear view thereof;

FIG. 3 is a left side view thereof, the right side view being a mirror image thereof;

FIG. 4 is a top view thereof; and,

FIG. 5 is a bottom view thereof.

The broken line showing of a hook is for illustrative purposes only and forms no part of the claimed design.
